UNITED STATES PATENT OFFICE.

JOHN L. HAYES, OF CARNEGIE, PENNSYLVANIA.

GAME-BOARD.

1,279,691.

Specification of Letters Patent. Patented Sept. 24, 1918.

Application filed November 7, 1917. Serial No. 200,771.

To all whom it may concern:

Be it known that I, JOHN LEO HAYES, a citizen of the United States, residing at Carnegie, in the county of Allegheny and State of Pennsylvania, have invented certain new and useful Improvements in Game-Boards, of which the following is a specification.

This invention relates to game boards and 10 has as its object to provide a game board for use in playing a war game involving the elements of chance and skill.

The aim of the invention is to provide a game board designated for the playing of 15 a game which will be highly interesting and which will permit of the players choosing, as their judgment dictates, whether they shall move their game pieces to an advanced position or whether they shall 20 depend upon the element of chance in an endeavor to remove from the board one or another of their opponent's game pieces.

In the accompanying drawings:—

Figure 1 is a plan view of one half of the 25 game board embodying the present invention.

Fig. 2 is a plan view of the other half of the board,

Fig. 3 is a perspective view of one of the 30 game pieces representing a fort,

Fig. 4 is a similar view of another one of the game pieces representing a ship.

For convenience sake, the board may be formed in two halves as illustrated in the 35 drawings which may either be disconnected from each other and adapted to be assembled edge to edge or which may be hingedly connected in any suitable manner, or the board may be of one piece construction. In any

40 event the playing surface of the board is divided into land fields 1 and 2 and a water field indicated in general by the numeral 3, this water field occupying the portion of the surface of the board not occupied by the

45 land fields 1 and 2. The land fields 1 and 2 are preferably located at opposite sides and diagonally opposite corners of the playing surface and may be of any desired configuration and size. Each land field is

50 designated by some suitable symbol, such for example, as the stars 4 and 5 shown in the drawings and indicating respectively, the land fields 1 and 2, the stars representing further the capitals of the belligerent

55 countries. In the present instance, the star 4 will be, for example, red in color and the

star 5 will be blue and these colors will also distinguish or indicate game pieces employed by the two players. One of these game pieces is clearly shown in Fig. 4 of 60 the drawings and comprises a preferably circular base 6 having thereon a small representation of a ship as indicated by the numeral 7, the bases of the game pieces employed by one player being red and the 65 bases of the game pieces employed by the other player being blue. Each player will, of course, be provided with a certain definite number of the game pieces and preferably each player will employ six of the pieces 70 6 in playing the game. Other game pieces such as shown in Fig. 3 of the drawings are also employed and each of these game pieces is preferably in the nature of a flat circular disk 8 having its upper surface, indicated 75 by the numeral 9, of a distinguishing color except at its center where there is a white area 10 bearing a designating numeral. The game pieces 8 represent forts and the same are to be disposed upon fortification bases 80 located at intervals along the land fields 1 and 2, these bases being preferably indicated by concentric circles as at 11 and being designated by numerals to which the numerals upon each of the several game pieces 85 8 correspond so that the players of the game will be assisted in properly placing the game pieces 8.

The water field 3 of the board is divided into neutral and belligerent zones and the 90 neutral zone is indicated in general by the numeral 12, this zone occupying the greater portion of the area of the said field 3. At the center of the field there is a belligerent zone 13 defined by a border line 14 or this 95 zone may be indicated by a suitable designating color. At the opposite sides of the zone 13 and along each of the land fields 1 and 2 there are located other belligerent zones indicated by the numeral 15 and each 100 of these zones is indicated by being printed in a distinguishing color. The zones 15 are each located opposite a representation of one of the fortification bases 11 and when the game pieces 8 are properly arranged upon the board each game piece will be located upon the fortification base opposite or next adjacent the belligerent zone 15 which bears the same distinguishing color as the surface 9 of the said game piece. 110

A number of paths are laid out upon the board as indicated by the numeral 16, these

paths following various lines and directions and extending through both the neutral and belligerent zones, 3, 13 and 15. Each path has located in its length at various intervals, positions or stops 17 some of which are located within the neutral zone 3, some within the belligerent zone 13, and the remainder in the various belligerent zones 15. The positions or stops 17 which are located 10 within the belligerent zones 13 and 15 are designated by colors which serve a purpose in the playing of the game.

In playing the game, assuming that the game pieces 8 have been placed upon their 15 respective fortification bases 11, the players will alternately forwardly or backwardly move their game pieces 6, one at a time, over the paths upon the playing surface of the board and from one position 17 to another substantially as in the playing of the well-known game of checkers. At diagonally opposite corners of the board there are positions 19 which represent the naval bases for the game pieces 6 representing the ships 25 comprising the fleets of the belligerent countries and it is from these positions that the players begin their moves, starting from any one of the points A, B, C or D indicated upon the board. Each player has as an object to so advance his game pieces as to eventually land one of them in the other player's capital. Should the two players each have one of his game pieces 6 in the same belligerent zone, the player whose move 30 is may either move one of his game pieces 6 or may depend upon the element of chance by throwing dice, in which event, and if the number thrown is the same as the number upon the position 17 occupied by his opponent's game piece 6 in the said belligerent zone, his opponent's ship is assumed to be destroyed and the game piece is removed from the board. This also applies to the game pieces 8, representing forts, and under 35 these circumstances the game pieces 8 have in a sense the same status as the game pieces 6. For example, one of the players may

have one of his game pieces 6 in one of his opponent's belligerent fields 15 and if he so desires he may, it being his play, throw dice 50 in an effort to remove his opponent's fortification game piece 6, which is accomplished if the number thrown is the same as the number of the position occupied by the said opponent's game piece. 55

Having thus described the invention, what is claimed as new is:

1. A game board having its playing surface divided into fields representing land and water, the water field being divided into 60 neutral and belligerent zones, the belligerent zones being individually identified, and paths upon the board provided at intervals with positions some located within the neutral zones and the others within the belligerent zones, the positions within the belligerent zones being individually numbered.

2. A game board having its playing surface divided into fields representing land and water, the water field being divided 70 into neutral and belligerent zones, the belligerent zones being individually identified and the land fields having fortification bases each related to a particular one of the belligerent zones, the surface of the board having 75 paths thereon provided at intervals with positions located within the water field, the positions within the belligerent zones being individually numbered.

3. A game board having its playing surface divided into fields representing land and water, the water fields being divided into neutral and belligerent zones, the belligerent zones being individually identified and the land fields having fortification bases each related to a particular one of the belligerent zones and individually numbered, the board 85 having paths upon its surface provided at intervals with positions certain of which are located within the belligerent zones and are 90 individually numbered.

In testimony whereof I affix my signature.

JOHN L. HAYES. [L. S.]
